ELECTRONIC THERMOMETER INSTRUMENT CASE

Ulf Helgesson, Woodland Hills, Calif., assignor to
Diatek, Inc.

Filed Mar. 16, 1972, Ser. No. 235,469

Term of patent 14 years

Int. Cl. D10—04

U.S. Cl. D52—7 R

FIG. 1.

FIG.
2.

FIG.
3.

FIG. 4.

FIG. 5.

FIG.
6.

FIG. 1 is a front perspective view of an electronic thermometer instrument case showing my new design;

FIG. 2 is a top plan view thereof;

FIG. 3 is a right side elevational view, the left side being a mirror image thereof;

FIG. 4 is a front elevational view thereof;

FIG. 5 is a rear elevational view thereof; and

FIG. 6 is a bottom plan view thereof.

I claim:

The ornamental design for an electronic thermometer instrument case, as shown and described.
